UNITED STATES PATENT OFFICE.

JOHN L. MIKOVITS AND FRANK PETERSELL, OF EAST PITTSBURGH, PENNSYLVANIA.

PHONOGRAPH-RECORD-CLEANING BRUSH.

Application filed November 15, 1923. Serial No. 674,854.

To all whom it may concern:

Be it known that we, JOHN L. MIKOVITS and FRANK PETERSELL, citizens of Austria, residing at East Pittsburgh, in the county 5 of Allegheny and State of Pennsylvania, have invented certain new and useful Improvements in Phonograph-Record-Cleaning Brushes, of which the following is a specification.

10 This invention relates to new and useful improvements in phonograph record cleaning brushes.

An important object of the invention is to provide a record cleaning brush for phonographs which may be mounted in a convenient position with respect to the turn-table of the machine and which may be manually moved into its operative position and be retained in such position without requiring the 15 attention of the operator of the machine.

A further object of the invention is to provide a brush of the above-mentioned type which may be moved into an inoperative position out of the way of the operator of the machine and the record carrying turn-table.

Other objects and advantages of the invention will be apparent during the course of the following description.

30 In the accompanying drawing forming a part of this specification and in which like numerals are employed to designate like parts throughout the same,

Figure 1 is a side elevational view of the 35 phonograph record cleaning brush embodying this invention with the said brush in its operative position,

Figure 2 is a top plan view of Figure 1,

Figure 3 is an end elevational view of the 40 apparatus shown in Figures 1 and 2,

Figure 4 is an end elevational view of the brush support with the brush arm moved into a position at right angles to the holder arm and with the holder arm extending vertically,

Figure 5 is a side elevational view of the brush arm and brush material carried thereby,

Figure 6 is a top plan view of Figure 5,

Figure 7 is an end elevational view of Figure 5,

Figure 8 is a top plan view of the holder arm,

Figure 9 is a side elevational view of the arm shown in Figure 8,

Figure 10 is an end elevational view of the arm shown in Figures 8 and 9,

Figure 11 illustrates two side elevational views of a latch member employed for retaining the brush in its operative position, 60 the said views being taken at right angles to each other,

Figure 12 illustrates two side elevational views and a top plan view of a toothed bar carried by the holder arm and adapted to 65 be engaged by the latch member for retaining the brush in its operative position, and

Figure 13 illustrates an end and a side elevational view of a stop member employed for checking the movement of the holder 70 arm when the same is moved into a vertical position for carrying the brush into its inoperative position.

In the drawing, wherein for the purpose of illustration is shown a preferred embodiment of this invention, the numeral 5 designates the brush support in its entirety and the numeral 6 designates the brush in its entirety.

The brush support embodies a base plate 80 7 of substantially rectangular formation and having fastener receiving openings 8 which are employed for securing the support to the stationary table of a phonograph in a convenient position with respect to the turn-table.

Carried by the upper face of the base plate 7 and projecting vertically therefrom in spaced relation to each other, are the uprights 9 which are provided with the transversely aligned ears 10 having openings 11 85 formed therein, as illustrated in Figures 1 and 2.

An end wall 12 is formed integrally with the adjacent edges of the spaced uprights 9 and is intended to be positioned adjacent the peripheral edge of the turn-table 95 of the phonograph with which this record cleaning brush is employed.

The brush in its entirety consists of a holding arm 13 having an enlarged tubular bearing portion 14 position substantially intermediate its ends which is adapted for being positioned upon a pivot pin 15 which is

positioned within the openings 11 formed in the ears 10 of the uprights 9. By inspecting Figures 8 to 10 inclusive, it will be seen that this holder arm 13 is cut away at its outer end, as at 16 for forming one portion of an overlapping joint with the brush carrying arm which will be described at a later point. This cut away portion 16 is curved at its outer end 17 and at the shoulder portion 18 as illustrated. The cut away portion 16 is also provided with an aperture 19 which is adapted for receiving the means for connecting the holder arm and brush arm and which will be described at a later point. Adjacent to the curved shoulder 18, there is formed a pair of spaced openings 20, the utility of which will be described when the holding means for the arm is discussed in detail. The inner end of the holder arm 13 is provided with a counter sunk opening 21 which is adapted for receiving the screw element 22 employed for securing one end of the tension spring 23 to the said holder arm. This tension spring is connected at its lower end, as by the bolt 24, to the end wall 12 of the brush support.

In Figures 5 to 7 inclusive, there is illustrated the brush arm 25 having suitably secured to the lower face thereof the brush material 26 which may be felt, hair, silk, etc. The inner end of the brush arm 25 is cut away, as at 27 and is provided with an inwardly curved outer end 28 and inwardly curved shoulder 29 for coacting with the outwardly curved end 17 and outwardly curved shoulder 18 and the cut away end 16 of the holder arm 13. This cut away end 27 of the brush arm 25 is provided with an aperture 30 which is intended to cooperate with the aperture 19 formed in the end 16 of the holder arm for receiving the connector bolt 31, illustrated in Figures 1 to 3 inclusive, for pivotally connecting the said arms 13 and 25. It will be seen by inspecting Figures 1 and 2, that the washers 32 are positioned upon opposite sides of the overlapping joint formed between the brush arm and holder arm and that a wing nut 33 is positioned upon the bolt 31 and is adapted for being tightened to retain the arms 13 and 25 in their adjusted positions with respect to each other.

It will be seen that the holder arm 13, due to the downward pull of the tension spring 23, will be normally retained in a vertically extending position with the brush material 26 out of engagement with the turn table, not shown, of the phonograph. For the purpose of retaining the brush in its operative position, a toothed bar 34 is connected to the under face of the holder arm 13 by the screws 35 which pass through the openings 20 formed in said holder arm. This toothed bar is illustrated in Figures 1, 3 and 12 as having a top arm 34^a and a depending arm 34^b which is provided with the

teeth 34^c, the said depending arm 34^b being of arcuate formation. Secured to the inner face of one of the uprights 9, as by the bolt 36, is a latch member 37 which is formed of spring material, such as steel, and is provided with a substantially V-shaped outer end 37^a which is adapted for selectively engaging the teeth 34^c formed in the toothed bar 34 for retaining the entire brush in its operative position as illustrated in Figures 1 to 2 inclusive. The latch member 37 is provided with an aperture 37^b thru which a suitable means is inserted for connecting the same to the push button 38 which is slidably positioned in an aperture 39 formed in this upright 9 and provided for furnishing means for moving the latch member 37 out of engagement with the toothed bar 34 to permit the brush to be swung upwardly by the tension spring 23.

In Figures 1 to 3 inclusive and 13, there is illustrated a stop element 40 which is provided with a reduced externally threaded end 41 that is adapted to be passed through a suitable opening formed in the end wall 12 of the brush support 5 and to receive a nut 42 for retaining the said stop in a position for placing the angular end 43 substantially vertically below the pivot pin 15 carried by the aligned ears 10. It will be seen that this stop member 40 will limit the downward movement of the inner end of the holder arm 13 for causing the said arm to be retained in a vertical position when the latch member is not in engagement with the toothed bar.

The operation of this phonograph record cleaning brush is as follows. In Figures 1 to 3 inclusive, the various elements are shown in their operative positions and are in their proper positions for causing the brush material 26 to engage the top surface of the phonograph record, not shown. It will be seen that the holder arm 13 and brush arm 25 are retained in longitudinal alignment by the bolt and wing nut 31 and 33 respectively. The latch member 37 is in engagement with the proper tooth 34^c in the toothed bar 34 for retaining the arms 13 and 25 in a substantially horizontally extending position and also for retaining the holder arm 13 against the downward pull of the tension spring 23. When the operator of the phonograph desires to move the cleaning brush into an inoperative position out of the way of the turn table, the bolt and wing nut 31 and 33 respectively are loosened and the brush arm 25 is pivoted to assume a position at right angles to the holder arm 13 whereupon the wing nut 33 is again tightened upon the bolt 31 for retaining these arms in this fixed position. The push button 38 is then operated for disengaging the latch member 37 from the teeth 34^c of the toothed bar 34 and the tension

spring 23 will then pull downwardly upon the inner end of the holder arm 13 for moving this arm into a vertical position against the outer angular end 43 of the stop member 40. The holder arm 13 and brush arm 25 will be in the positions shown in elevation in Figure 4. It will be very apparent to those skilled in the art that when the brush is again to be moved into engagement with the grooved surface of the phonograph record, the arm 25 is moved into longitudinal alignment with the holder arm 13 and retained in this position by the bolt and nut 31 and 33 respectively. The said arms are then moved into a horizontal position, against the tension of the spring 23, and the teeth 34^a will be moved downwardly over the substantially V-shaped end 37^a of the latch 37 until the brush material is in its proper operative position. The latch and toothed bar will retain the arm in this adjusted position.

It is to be understood that the form of this invention as shown and described is taken as a preferred example of the same, and that various changes in the shape, size,

and arrangement of parts may be resorted to without departing from the spirit of the invention or scope of the subjoined claims.

Having thus described the invention, we claim:—

1. In a phonograph record cleaning brush of the type described, a support, a brush carrying arm pivotally connected to said support, means for retaining said brush carrying arm in a horizontally extending position, and means for swinging said arm into a vertically extending position when the arm is released by the aforesaid holding means.

2. In a phonograph record cleaning brush of the type described, a base, spaced uprights carried by said base, a brush carrying arm pivotally connected to said uprights, means associated with said arm and one of said uprights for retaining the arm in a horizontal position, and resilient means for moving said arm into a vertically extending position when said holding means is released.

In testimony whereof we affix our signatures.

JOHN L. MIKOVITS.
FRANK PETERSELL.
